CLAIM

The ornamental design for a belt rack, as shown and described.

DESCRIPTION

FIG. 1 is a perspective view of my new design for a belt rack;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of a portion of FIG. 2;

FIG. 9 is a sectional view along line 9—9 in FIG. 8;

FIG. 10 is a sectional view along line 10—10 in FIG. 8;

FIG. 11 is an enlarged view of a portion of FIG. 2 with the belt rack supporting plural belts, the belts form no part of the invention;

FIG. 12 is a rear view of FIG. 11;

FIG. 13 is a view along line 13—13 in FIG. 11; and,

FIG. 14 is a view along line 14—14 in FIG. 11.

1 Claim, 6 Drawing Sheets
